United States Patent Office.

CHARLES W. CAHOON, OF PORTLAND, MAINE.

Letters Patent No. 80,133, dated July 21, 1868.

IMPROVEMENT IN LAMPS.

The Schedule referred to in these Letters Patent and making part of the same.

TO ALL WHOM IT MAY CONCERN:

Be it known that I, CHARLES W. CAHOON, of Portland, in the county of Cumberland, and State of Maine, have invented a new and useful Improvement in Lamps; and I hereby declare the following to be a full, clear, and exact description thereof, which will enable others to make and use my invention, reference being being had to the accompanying drawings, forming part of this specification, in which—

Figure 1 is a side elevation of the lamp-burner and a section of the chimney.

Figure 2, another view of the same, with the chimney and deflector turned off from the burner.

Letters Patent of the United States have been granted upon lamp-burners, in which the chimney is held to the deflector by the said deflector fitting within the same, and pressing outwardly against the interior of the chimney.

My invention relates to an improvement in such burners or lamps, for the purpose of more securely holding or fastening the chimney in its position in relation to the burner.

In the accompanying drawings—

b shows a deflector; *d*, the wick-tube; *f*, is a perforated plate to admit a current of air to the flame; *h* is the chimney, passing down and around the deflector *b*; *e* shows the rest for the base of said chimney.

My improvement consists in constructing the chimney thus designated with an interior shoulder, as at *y*, or at that point on and around the interior of the chimney where the deflector meets and impinges upon the same. This shoulder is intended for the reception of the outer edge or periphery of the said deflector. It will be seen, from the drawings, that the chimney is made of that form in which the walls of the same are straight, or nearly so, to a distance, at least, somewhat above and below the point of contact between the outer periphery of the deflector and the interior of the chimney. Thus, the outer edge of the deflector fitting into the shoulder, constructed as described, serves securely to hold the chimney in its position around the deflector, the wick-tube, and the flame of the lamp when lighted.

It is apparent that a lamp-chimney of this description, constructed with a shoulder, as described, may be fastened to the burner by pressing the said chimney down over the deflector, until the said deflector meets the said shoulder.

As illustrated in fig. 2 of the drawings, a joint, *n*, unites the chimney-rest *e* with the perforated piece of metal *f*, whereby, when the chimney is secured as described, the chimney, deflector, and rest *e* can be turned off from over the wick-tube, as shown, without liability of the chimney to be shaken or to fall from its position around the deflector and on the rest *e*.

Letters Patent of the United States have been granted to me for a joint in its connection with a lamp, as therein shown, and I therefore do not claim such device or combination.

The operation of placing the chimney in its position around the deflector is simply to press the chimney downwardly until the base of the chimney reaches its rest, *e*, and the deflector has entered the interior shoulder of the chimney.

When the chimney is to be removed from over the wick-tube and flame of the lamp, the chimney, deflector, and rest *e* are turned off, as illustrated in fig. 2, by means of the joint.

I have described the part *y* as a shoulder, although it is represented in the drawing as a curvilinear projection on the outside of the chimney, and a curvilinear recess on the inside thereof. But it will be apparent that only the lower half or portion of the curvilinear part *y* serves, in fact, to aid in retaining the chimney in its position when thrown back, as in fig. 2.

When the chimney is erect, as in fig. 1, the chimney rests upon its base at *e*, and does not rest by the upper portion of the curvilinear part *y* pressing upon the upper side of the deflector. The same purpose would be subserved, were the upper part of the curvilinear part *y* left out, because the combination of the edge of the deflector with the lower portion of the curvilinear part *y* is what prevents the chimney from dropping when thrown back. The lower half or shoulder is the operating part, the entire recess or groove being made merely as a convenient method of construction.

What I claim as my invention, and desire to secure by Letters Patent, is—

1. In combination with a lamp-burner, to which the chimney is held by interior chimney-fastenings, a chimney having an interior shoulder, substantially as and for the purposes described.
2. In combination with a lamp-burner, to which the chimney is secured by means of an interior shoulder, the horizontal joint n , as and for the purposes described.
3. A lamp-chimney, as described, with an interior shoulder in the same, for the purpose of fastening it to the burner, substantially as set forth.

CHARLES W. CAHOON.
